HOLDING MEANS FOR TEST SPECIMENS

David C. Scott, Providence, R. I., assignor to
 Henry L. Scott Company, a corporation of
 Rhode Island

Application December 30, 1942, Serial No. 470,554

4 Claims. (Cl. 265—12)

This invention relates to the testing of flexible materials such as tapes, webbing, cord or other flexible like materials, the ends of which must be gripped for applying tension thereto in the performance of the test.

In performing a tensile test upon a flexible material it is difficult to obtain the proper grip upon the material so that the same will not slip or become misaligned during the test. It has been proposed to provide two jaws one of which is movable and to position an end of the material to be tested between the jaws and then wrap the material about the jaws so that the pull of the material will move one of the jaws toward the other and firmly grip the material which is located between the jaws. In order that the pull on the material being tested may be free from the material which is wrapped about the fixed jaw different expedients have been resorted to to accomplish this purpose, such for instance as making the fixed jaw smaller than the movable jaw so that the material being tested as it leaves the movable jaw will clear the fixed jaw. This arrangement while satisfactory from the standpoint of clearance does not always position the line of pull directly through the center line of the specimen when under test which is also desirable.

One of the objects of the invention is to provide a clamp in which the pulling of the specimen serves to hold the jaws of the clamp firmly upon the specimen and to properly align the specimen with reference to the pull thereon.

Another object of this invention is to so mount the clamp that the line of pull will be directly through the center of the specimen and the specimen will also leave one of the jaws at such location as to clear the other jaw and the part of the specimen wrapped thereabout.

Another object of this invention is to provide a pair of such jaws between which the specimens extend so mounted that when a pull is applied through the jaws to move the jaws directly away from each other the jaws will rock to locate the specimen so supported that it will extend along the line of the pull with the pull extending substantially through the center of the specimen regardless of its thickness.

Another object of the invention is to provide an arrangement for clamping the specimen initially which clamp may be removed as the test proceeds.

With these and other objects in view, the invention consists of certain novel features of construction, as will be more fully described and particularly pointed out in the appended claims.

In the accompanying drawing:

Fig. 1 is a top plan view showing the test specimen as supported by two of my improved clamps with tension applied to the clamp sup-

ports to locate the clamp in the relative position assumed while tension is applied;

Fig. 2 is an elevation of one of the main clamps alone;

Fig. 3 is an end view of the clamp shown in Fig. 4 with the auxiliary clamp in place;

Fig. 4 is a central sectional view of the clamps shown in Fig. 2 with the auxiliary clamp in dotted lines;

Fig. 5 is a detailed view of the auxiliary clamping means for holding the jaws in initial gripping position; and

Fig. 6 is an elevation illustrating a machine in which the clamps are mounted.

The testing machines in which my clamps are used are any of the well-known types of testing machines for testing the tensile strength of textile materials. The horizontal type machine such as illustrated herein may be found in the testing machine of Patent No. 1,911,006 dated May 23, 1933, or No. 2,205,579 dated June 25, 1940, although it will be appreciated that the arrangement of clamps such as shown herein may be disposed vertically if desired.

The test specimen designated 10 is held at each of its end portions by clamps designated generally 11 and 12, one of which may be held and the other of which may be moved so as to apply tension on the specimen or both may be movable in opposite directions or one moved while the other is moved against a certain resistance that a load may be applied. The support for one clamp is designated 13 and the support for the other clamp 14 and in the arrangement here shown the support 14 is moved by some power means such for instance as a thread shaft 15 while the support 13 is held fixed against movement.

The ends of these supports 13 and 14 are threaded as at 20 and the body portion 21 provided with a threaded socket 22 is screwed onto the support 13 or 14 as may be desired. This body is reduced (see Fig. 4) to provide a stud 23 through which a pin 24 extends which is headed and provided with a cleat at one end and is threaded as at 25 at the other end. Member 26 is pivotally mounted upon the stud 23 and is held against escape from the stud by a washer 27 held snugly against the end of the stud by the nut 28 screwed on to the pin 24. The thickness of the collar of the member 26 is less than the length of the stud so that it has freedom of motion about the stud in a pivotal relation. However, there extends stops 29 and 30 from the body 21 which will be engaged by a pin 31 on the member 26 to limit the pivotal movement of the member 26 about the stud 23.

The member 26 is conveniently fashioned, as by casting, with a fixed jaw 32 provided at the outer end thereof. The surface 33 thereof distant from the pivotal mounting 23 is half round

while its surface toward the pivot 24 is flat on substantially a diametrical line through the center of the arc of the rounded surface 33. This flat surface presents one of the gripping faces of the jaw. The member 26 is provided with a slot 35 and the movable jaw designated generally 36 is slidably guided in this slot while a plate 37 attached as at 38 to the underside of the jaw 36 prevents the jaw from being lifted upwardly as seen in Fig. 4 out of the slot 35. This jaw 36 may move toward the jaw 32 by sliding along the slot 35 which extends in line with the center of the pivot of the stud 23 and the center of the arc of the rounded fixed jaw 33. This movable jaw also has a rounded surface 38 substantially on the arc of a circle and a flat surface 39 which is on a diametrical line substantially through the center of the arc of the rounded surface 38. This flat surface 39 is roughened or serrated by means of notches 40 so as to provide a better holding surface for the end of the specimen which is placed between the jaws to be engaged by the surfaces 34 and 39. It will be apparent that the rounded surface 33 is of a smaller radius than the rounded surface 38.

To load the specimen into the device the two clamps are brought sufficiently close together so that the ends of the specimen may be readily fed into each of the clamps. One end of the specimen 10 which is designated 41 is passed through a slot 42 in the fixed jaw and there doubled upon itself as at 43 (see Fig. 1). The specimen is then led between the gripping surfaces 36 and 39 as at 44 and then wrapped around the curved surface 33 of the fixed jaw as at 45, then about the curved surface 38 of the movable jaw as at 46 (see Fig. 1) and then to the other clamp where a similar disposition of the end portion of the specimen to be tested is provided to secure it in position in the companion clamp. The pull on this specimen is directed along the line of the supports 13 and 14 and the center of the pivots upon which the members 26 of the clamps are mounted are in this line of pull thus the center of the studs 23 are in the line of the pull along the supports 13 and 14. As the pull commences the member 26 will rock about the pivots 23 until the specimen 10 is disposed along the center of pull through the supports 13 and 14 and the pivots 23 for the members 26. Thus all of the pull is directed through the center of the specimen. The members 26 rock so as to provide for this while at the same time it will be apparent that the specimen 10 leaves the clamp 11 at a tangent directly below the center of the pivot of the clamp so that the specimen pulls free from contact with any other part of the specimen which is wrapped around the jaws in order that the directed pull may cause the movable jaw to more firmly press this movable jaw toward the fixed jaw without any retarding friction and firmly grip the part of the specimen designated 44 which is between the jaws. By this arrangement a very firm grip on the end portion of the specimen is had and the greater the pull the greater the grip to hold the specimen fixedly in position.

It is apparent, however, that prior to the exerting of some pull upon the specimen it is desirable to clamp the jaws together and accordingly I have provided a pair of arms 45 and 46 with a screw 47 freely rotatable in an opening 48 in the arm 45 and threaded into an opening 49 in the arm 46 by means of an abutment head 50. Another screw 51 has an end 52 abutting the arm

45 while it is threaded through opening 53 in the arm 46. The screw may be moved by reason of a handle 54. This clamp is positioned in the hollow portions 55 and 56 of the jaws and the jaws are initially held together until tension upon the specimen commences then these auxiliary clamps may be removed or may be left in place as desired for the remainder of the test.

I claim:

10 1. In a testing machine, a clamp support, a member pivotally mounted thereon, a clamp carried by said member at a point spaced from said pivot mounting and comprising fixed and movable jaws, said fixed jaw being distant from said pivotal mounting and the movable jaw being movable toward and from the fixed jaw whereby the specimen to be tested may be positioned between the jaws of the clamp and wrapped about the fixed jaw and then about the movable jaw to extend toward a means to hold the other end so that when tension is applied through the said support the member will rock to dispose the specimen toward the line of pull through said pivotal mounting.

15 2. In a testing machine, a clamp support, a member pivotally mounted thereon, a clamp carried by said member at a point spaced from said pivot mounting and comprising fixed and movable jaws, said fixed jaw being distant from said pivotal mounting and the movable jaw being movable along a line between the fixed jaw and pivotal mounting toward and from the fixed jaw along a line between the fixed jaw and pivotal mounting whereby the specimen to be tested may be positioned between the jaws of the clamp and wrapped about the fixed jaw and then about the movable jaw to extend toward a means to hold the other end so that when tension is applied through the said support the member will rock to dispose the specimen toward the line of pull through said pivotal mounting.

20 3. In a testing machine, clamp supports each having a pivot, a member mounted to rock on each of said pivots, and a clamp carried by each 25 of said members at points spaced from said pivots each clamp comprising a half round jaw fixed on the outer end of the member and a half round movable jaw movable toward the fixed jaw whereby the specimen to be tested may be positioned between the jaws of a clamp and wrapped about the fixed jaw and then about the movable jaw to extend toward the other clamp and means to exert a pull in opposite directions on said pivots whereby when tension is applied the members 30 may be rocked to dispose the specimen in the line of pull between said pivots.

35 4. In a testing machine, a clamp support, a member pivotally mounted thereon, a clamp carried by said member at a point spaced from said 40 pivot mounting and comprising fixed and movable jaws, said fixed jaw being distant from said pivotal mounting and the movable jaw being movable toward and from the fixed jaw whereby the specimen to be tested may be positioned between the jaws of the clamp and wrapped about the fixed jaw and then about the movable jaw to extend toward a means to hold the other end so that when tension is applied through the said support the member will rock to dispose the specimen toward the line of pull through said pivotal mounting and means to initially clamp the jaws together upon the specimen.

45 DAVID C. SCOTT.
